MACHINE FOR OPERATING UPON SHOES

Alfred S. Clark, Beverly, Mass., assignor to United
Shoe Machinery Corporation, Flemington, N. J.,
a corporation of New Jersey

Application November 18, 1942, Serial No. 465,975

36 Claims. (Cl. 12—34)

This invention relates to machines for operating upon shoes, and more particularly to machines for leveling the bottoms of shoes. The invention is herein illustrated with reference to that type of machine having a leveling tool, such as a roll, and a shoe support mounted for swinging movements in directions lengthwise of a shoe thereon to cause the leveling tool to operate progressively along the shoe bottom and in which the movements of the shoe support are effected by power-operated means continuously under the control of the operator.

An object of the invention is to provide in a machine of the above-mentioned type fluid-pressure means for operating the leveling tool to apply leveling pressure to the bottom of a shoe. Preferably the fluid-pressure means for thus operating the leveling tool is under the control of the operator so that he may cause the pressure of the tool on the shoe bottom to be varied as desired to meet different conditions of work or the tool to be lifted out of engagement with the shoe when it is desired to level only selected portions of the shoe bottom.

As illustrated herein, a fluid-pressure motor constantly acts on the tool to force it against the shoe bottom, and a second fluid-operated motor is also connected to the tool in such a manner that when full power is applied by the second motor the tool is lifted out of engagement with the work against the force of the first motor. By varying the power output of the second motor, which is readily accomplished by varying the amount of pressure fluid admitted thereto, the effect of the first fluid motor may be only partially overcome so that the pressure of the leveling tool on the work may be varied as desired or as necessary in operating upon different kinds of work or different portions of the bottom of a shoe. The flow of pressure fluid to the second motor is controlled by a valve operated by a hand lever, so that upon movement of the valve in one direction the motor operates to exert a lifting force on the leveling tool. By means of a connection between the leveling tool and the valve, the valve is caused to move toward closed position in response to upward movement of the leveling tool so that the extent of upward movement is proportionate to the movement of the hand lever by which the operator controls the valve. Provision is made in accordance with a feature of the invention for permitting idle movement of the movable element of the second motor in response to variations in the heightwise position of the tool when full pressure is

applied by the tool on the work, thereby to compensate for variations in the heightwise curvatures of shoe bottoms of different styles. In order that this heightwise movement of the tool will not operate the valve by which the second motor is controlled, the connection between the tool and the valve is such that no motion is imparted to the valve at this time.

Another object of the invention is to provide in a machine of the above-mentioned type fluid-pressure means for holding the leveling tool initially in a position higher than it occupies in operating on the shoe and for moving it automatically into engagement with the toe end of the shoe bottom at a predetermined time in the movement of the shoe support prior to the operation of the tool upon the shoe. By thus holding the tool in this position until the shoe support has been moved rearwardly to carry the shoe beneath the leveling tool, interference is prevented between the tool and the toe end of the sole and pressure is applied in proper relation to the toe end of the sole. This movement of the leveling tool is effected, in accordance with the illustrated embodiment of the invention, by connecting the jack and the valve which controls the second motor referred to above, so that the valve is automatically opened upon movement of the jack into loading position. The second motor holds the tool in its elevated position until the jack moves rearwardly to carry a shoe beneath the tool, whereupon the valve is closed and the tool is forced downwardly by the first fluid pressure motor in proper relation to the toe end of the sole.

Another object of the invention is to provide in a fluid-pressure-operated system having a fluid-pressure motor, improved means for automatically varying the pressure of the operating fluid so that initially fluid under low pressure is supplied to the motor and after the motor has moved from its initial position, fluid under high pressure is automatically supplied thereto. This is accomplished in the illustrated embodiment of the invention by providing the pump which supplies the pressure fluid to the motor with a pressure relief valve for determining the maximum pressure of the operating fluid and a restricted by-pass which, when open, diverts a portion of the operating fluid from the motor. When the motor is in an initial rest position, the by-pass is open, but is automatically closed after initial operation of the motor by permitting flow of the pressure fluid thereto. This arrangement minimizes the load on the pump when the ma-

chine is at rest while supplying sufficient pressure fluid to initiate operation of the machine after which fluid under high pressure is made available for the operation of the machine.

The above and other features of the invention, including various novel details of construction and combinations of parts, will now be more particularly described by reference to the accompanying drawings and pointed out in the claims.

In the drawings,

Fig. 1 is a perspective view of a machine in which the invention is embodied;

Fig. 2 is a perspective view partly in section illustrating the mounting for the leveling roll;

Fig. 3 is a perspective view illustrating the fluid-pressure mechanism for operating the jack;

Fig. 4 is a view in side elevation of the connections between the jack and the motor for elevating the leveling roll when the jack is moved to loading position;

Fig. 5 is a perspective view of the fluid-pressure mechanism for tipping the roll;

Fig. 6 is a perspective view of the fluid-pressure mechanism for lifting the roll; and

Fig. 7 is a diagrammatic view of the fluid-pressure system for operating the machine.

The machine illustrated herein includes a supporting frame comprising vertical side walls 10, an end wall 12 and a horizontal lower supporting wall 14. This latter wall forms the top wall of a reservoir 16 which contains a supply of pressure fluid by which the machine is operated. Pivoted on a shaft 18 extending between the side walls 10 at their forward portions is a sleeve 20 carrying a jack 22 to which swinging movements are imparted by power-operated means under the control of the operator, as herein-after described, to carry a shoe supported by the jack rearwardly and forwardly beneath a leveling roll 24 which is forced down on the shoe bottom to apply leveling pressure progressively to the sole and to which tipping movements may be imparted by separate power-operated means also under the control of the operator to cause the leveling pressure to be applied to the margins of the sole.

The jack 22 comprises a toe post 26 and a heel post 28 carrying respectively a toe-supporting pad 30 and a spindle 32 arranged to enter the spindle hole in the heel portion of a last. Whereas the jack illustrated herein is of simplified construction, it will be understood that any suitable form of jack may be employed, such for example as that illustrated in Letters Patent of the United States No. 2,230,244, granted February 4, 1941, on an application of F. V. Hart et al. Swinging movements are imparted to the jack by means of an arm 34 fast to the sleeve 20 and depending therefrom. The lower end of this arm is connected by a pivot pin 36 to a rearwardly extending link 38 (Fig. 3), the rearward end of which is pivoted at 40 to the forwardly extending rod 42 of a piston 44 (Fig. 7). This piston is slidable in a cylinder 46 which is connected by pipes 48 and 50 to a valve chamber 52 containing a valve member 53 which controls the flow of pressure fluid into the cylinder 46. The valve chamber 52 is provided with a pair of intake ports 54 and 56 connected to a pipe 58 which is in turn connected to a manifold 60 into which pressure fluid is forced by a pump 62. The valve member 53 includes a valve element 66 which normally closes both of the intake ports 54 and 56 as shown in Fig. 7 thus preventing the

flow of pressure fluid to the cylinder 46. Upon movement of the valve member 53 to the left (Fig. 7) the port 56 is uncovered, whereupon the pressure fluid flows through the pipe 50 into the cylinder 46 rearwardly of the piston 44 to move the piston to the left and cause rearward swinging movement of the jack 22. Similarly, upon movement of the valve member 53 to the right, the valve port 54 is uncovered so that the pressure fluid flows through the pipe 48 into the chamber 46 ahead of the piston 44 to move the piston and the jack in the reverse directions. The rearward wall of the cylinder 46 is closed by a plate 68 and the forward end of the cylinder is provided with a cap 70 from which projects a tube through which the piston rod 42 slides. Within the cylinder and near its forward end is a wall 72 providing a compartment between it and the cap 70 which communicates by way of a pipe 74 with the fluid reservoir. When the piston is being moved toward the left by reason of the movement of the valve member 53 in the same direction, the fluid ahead of the piston escapes through the pipe 48 and a pipe 75 which opens into the valve chamber and is uncovered at this time by an element 76 of the valve member to permit the fluid to flow into a pipe 78 communicating with the reservoir. By the use of the double wall construction afforded by the cap 70 and the wall 72 around the piston rod at the forward end of the cylinder, it is unnecessary to provide packing for the piston rod as any fluid which leaks past the wall 72 will pass into the reservoir by way of the pipe 74. The valve member 53 also includes a valve element 80 which normally closes a pipe 82 leading to the fluid reservoir but which uncovers this pipe upon movement of the valve member to the right to permit discharge of the pressure fluid behind the piston 44 through the pipe 50 when the piston is moved to the right by the pressure fluid entering the cylinder ahead of the piston by way of the port 54.

Operation of the valve member 53 to control the flow of pressure fluid into the cylinder 46 of the jack-operating motor is controlled by a hand lever 84 (Fig. 1) pivotally connected to the left side wall 10 of the machine frame by a pivot pin 86. The lever 84 is connected by a link 88 to an arm 90 the lower end of which is pivotally connected at 92 to a stem 94 of the valve member 53. The upper end of the arm 90 is supported for limited movement by a slotted bracket 96 secured to the adjacent wall 10. The arm 90 is also connected for movement with the jack 22 by a link 98 pivoted to an arm 100 extending upwardly from the jack-supporting sleeve 20. With the jack at rest, rearward movement of the operating lever 84 will cause the arm 90 to pivot about its connection to the link 98 and move the valve member 53 forwardly or to the left as viewed in Fig. 7 to uncover the port 56. Fluid under pressure now passes through the port and into the cylinder 46 behind the piston 44, thus moving the piston to the left and through the connections heretofore described, swinging the jack rearwardly. As the jack moves rearwardly it acts through the link 98 to swing the arm 90 about its connection with the link 88 connected to the operating lever 84, thus moving the valve member 53 in the reverse direction until the valve member assumes the position shown in Fig. 7 with both ports 54 and 56 closed. Thus the jack is moved a distance corresponding to the extent of movement of the lever 84.

after which the valve member 53 is returned to its closed position, and the jack comes to rest. It will be understood that continuous movement is imparted to the jack as long as the lever 84 is moved continuously. There is thus provided a simple follow-up mechanism for the valve operated by the movement of the jack, so that the jack moves a distance corresponding to the movement of the operating lever 84 and always moves in the same direction as the operating lever.

During the operation of the machine it is desirable to prevent the jack from moving forwardly far enough to carry the toe end of the shoe out of engagement with the leveling roll. Accordingly, provision is made for normally preventing such movement of the jack once the jack has been moved from the loading position illustrated in Fig. 1 into position to carry the toe end of the shoe under the roll. For this purpose a latch 102 is pivoted to the left side walls of the machine on a pivot pin 104 and is urged in a counterclockwise direction by a spring 106 connected between the latch and the frame of the machine. The rearward end of the latch is upwardly curved at 108 and cooperates with a pin 110 carried by the arm 90 to prevent forward movement of the arm to the position shown in Fig. 1 during the leveling operation. As illustrated, when the jack is in loading position the pin 110 is located in engagement with the upper surface of the curved portion 108; but upon rearward movement of the operating lever 84 to swing the jack rearwardly, the pin 110 rides over the curved end portion 108 thus exerting a cam action on the latch 102 to move it in a clockwise direction until the pin clears the end of the arm, after which the spring 106 again moves the latch into the position shown, against a stop pin 112 carried by the frame of the machine. Accordingly, upon forward movement of the arm 90 in response to a corresponding movement of the lever 84 the pin 110 will engage the rearward face of the latch 102, thereby limiting forward movement of the arm 90 to prevent the jack from being swung forwardly far enough to carry the toe end of the shoe beyond the leveling roll 24. Mechanism is provided for swinging the latch in a clockwise direction when it is desired to permit return of the jack to loading position. For this purpose the latch 102 is provided at its lower end with a pin 114 arranged to be engaged by the upper end of an arm 116 extending upwardly from a sleeve 118 journaled on a shaft 120 supported in the lower portion of the frame of the machine. The sleeve 118 is also provided with a forwardly extending treadle 122 by depression of which the arm 116 may be moved forwardly against the force of a spring 124 to impart clockwise swinging movement to the latch 102 to move its rearward end portion 108 out of the path of the pin 110, thus permitting the arm 90 to be moved by the operating lever 84 to the forward end of the slot in the bracket 96 as shown in Fig. 1. Rearward movement of the jack during the leveling operation is limited by an arm 125 engageable with an adjustable stop screw 127 carried by a bracket 129. As the jack swings rearwardly, the arm 125 swings forwardly and, by its contact with the stop screw, it prevents the jack from swinging rearwardly beyond a predetermined position.

When the jack is in its loading position the high-pressure side of the pump 62 is connected

directly to the reservoir 16 by a pipe 126 and a by-pass valve 128, thereby to reduce the load on the pump. As shown in Fig. 7 the by-pass valve 128 comprises a valve chamber 130 secured to the wall 14 and a valve member 132. When the valve member is in the position shown in Fig. 7 a port 134 is uncovered so that the pressure fluid may flow directly through the pipe 126 and a pipe 136 into the fluid reservoir. The forward end of the valve member 132 is connected by a link 138 to the lower end of an arm 140 (Fig. 1), the upper end of which is pivoted to the right-hand side wall 10 of the machine frame. The arm 140 is formed with an upwardly curved slot 142 which receives a cam roll 144 on the rearward end of an arm 146 secured to the jack-supporting sleeve 20. Upon initial rearward movement of the jack from its loading position the cam roll 144 moves downwardly and acts on the arm 140 to move it forwardly, thereby moving the valve member 132 forwardly or to the left as viewed in Fig. 7 to close the port 134 thus cutting off the by-pass for the pump 62, whereupon the full pressure of the pump is available to move the jack and to operate the leveling roll as described hereinafter. The shape of the slot 142 in the arm 140 is such that the valve member 132 remains in closed position throughout the leveling operation and until the jack is returned into loading position. In order to maintain some pressure in the system when the jack is in its loading position, a manually adjustable valve 148 is provided in the pipe 126 to control the flow through the by-pass when the valve 128 is open. The pressure in the system may be readily observed by a gage 150 connected to the manifold 60.

The leveling roll 24 is carried by the forwardly extending arms 152 of a support 154 having downwardly extending flanges 156 through which pass a pivot pin 158. The pin 158 is carried by a bracket 160 (Fig. 2) fixed to a shaft 162 supported for rocking movement in spaced bearings 164 and 166 (Fig. 1). The support 154 is connected at its rearward end by a link 168 to a pair of bell-crank levers 170 fulcrumed on a pin 172 carried between the rearward ends of arms 174 (Fig. 2) of a lever 176 secured to the shaft 162 on the opposite side of the bearing 164 from the bracket 160. The lower end of the bell-crank levers 170 carry rolls 178 which are received between flanges 180 of a sleeve 182 slidable on the shaft 162. Upon sliding the sleeve 182 along the shaft 162 motion is transmitted through the bell-crank levers 170 and the link 168 to rock the roll support 154 about the pin 158, thereby to vary the heightwise position of the leveling roll. Upon movement of the lever 176 to rock the supporting shaft 162 in its bearings 164 and 166 the supporting frame 154 is rocked about the axis of the shaft 162 thereby to tilt the leveling roll relatively to the work.

During the leveling operation, the leveling roll is held by fluid pressure against the bottom of the shoe being operated upon. For this purpose a motor 184 (Figs. 1 and 7) comprising a cylinder 186 and a piston 188 is provided. The lower portion of the cylinder is connected by pipes 190 and 192 to the manifold 60 so that the pressure fluid always acts upon the lower side of the piston 188, tending to move it upwardly within the cylinder. The upper end of the cylinder is connected by a pipe 194 to the fluid reservoir. The piston 188 includes an upwardly extending piston rod 196 which is connected by a link 198 (Fig. 1)

to a lever 200 pivoted at its forward end on a pin 202 supported by a brace 204 extending between the side walls 10 of the machine frame. The rearward end of the lever 200 is connected by a link 206 between arms 208 secured to a sleeve 210 mounted on a shaft 212 supported by the side walls 10. The sleeve 210 carries a lever 214 having a forked upper end carrying blocks 216 engaging opposite sides of the sleeve 182 between spaced flanges 218 of the sleeve. Upon upward movement of the piston 188 the rearward end of the lever 200 is moved upwardly, causing the sleeve 210 to be turned in a clockwise direction (Fig. 1) about the shaft 212, thus moving the upper end of the lever 214 rearwardly. The sleeve 182 is thus moved rearwardly on the shaft 162 and acts through the bell-crank levers 170 and the link 168 to rock the roll support 154 in a direction to move the roll 24 downwardly against the work.

At the completion of a leveling operation when the jack is moved forwardly to its loading position and while the machine is at rest with the jack in this position, it is desirable that the roll 24 be held above the work as illustrated in Fig. 1 so that undue pressure will not be exerted upon the toe end of the shoe when the jack is moved rearwardly to carry the shoe beneath the leveling roll. It is may also be desirable to vary the pressure of the roll on the shoe during the leveling operation or to lift the roll entirely out of contact with the shoe to avoid applying pressure to certain portions thereof. Accordingly, an additional motor 220 (Figs. 1 and 7) is provided for lifting the roll against the force exerted by the motor 184. The motor 220 comprises a piston 222 movable in a cylinder 224 similar in construction to the cylinder 46. Extending outwardly from the rear end of the cylinder is a piston rod 226 connected by a pin 228 (Fig. 1) to the lower end of the lever 214 carried by the sleeve 210. Upon the introduction of fluid under pressure into the forward end of the cylinder 224 the piston 222 is moved rearwardly to rock the lever 214 in a counterclockwise direction, thus causing the roll 24 to move upwardly, the moment arm between the piston 222 and the axis of the lever 214 being substantially greater than that between the piston 188 and the axis of the lever so that the motor 220 is able to overcome the effect of the motor 184.

For controlling the operation of the piston 222 a valve member 230 is provided slidable within a valve chamber 232. The valve chamber is connected by a pipe 234 to the manifold 60 and flow of pressure fluid through this pipe into the forward end of the cylinder 224 is controlled by an element 236 of the valve 230 which normally closes the valve chamber 232 from the pipe 234. Upon movement of the valve member 230 forwardly of the machine or to the left as viewed in Fig. 7, pressure fluid flows through the pipe 234 and a pipe 238 connecting the valve chamber 232 and the cylinder 224 to move the piston 222 rearwardly, thereby elevating the roll 24. A pipe 240 provides communication between the rearward end of the cylinder 224 and the fluid reservoir. When the valve member 230 is in the position shown in Fig. 7 the piston 222 is free to move within the cylinder in response to variations in the height of the leveling roll during the leveling operation as different portions of the shoe bottom are traversed. For thus permitting this freedom of movement of the piston 222 at this time the forward end of the cylinder 224 is connected

by the pipe 238, the valve chamber 232 and a pipe 242 to the lower end of a surge tank 244 mounted above the motor 220. A pipe 246 provides communication between the fluid reservoir and the surge tank which is in the form of a closed receptacle so that a predetermined column of pressure fluid may be retained therein. Communication between the forward end of the cylinder 224 and the fluid reservoir by way of the surge tank is cut off by an element 248 of the valve member 230 when the valve member is moved forwardly to elevate the leveling roll.

Operation of the valve member 230 is controlled by a treadle 250 (Fig. 1) secured to a sleeve 252 carried by the shaft 120. Also carried by this sleeve is an upwardly extending arm 254 to which is pivoted the forward end of a link 256, the rearward end of which is slotted at 258 to receive a pin 259 extending through a vertically extending arm 260 (Fig. 5) thus forming a pin-and-slot connection with the arm. The lower end of the arm 260 is pivoted to a valve stem 262 of the valve member 230 and the upper end of the arm is connected by a link 263 to the lever 214 (Fig. 1) by which the vertical movement of the leveling roll is effected.

The treadle 250 is maintained in raised position, as shown in Fig. 1 by a spring 264 connected between the arm 254 and a pin secured to the wall 14 of the machine frame. An adjustable stop, comprising a screw 266 threaded through a bracket 268 carried by the arm 254, by its engagement with the adjacent portion of the machine frame limits the upper position of the treadle. Upon depressing the treadle 250 the arm 260 connected to the valve stem 262 swings about its connection to the link 263, after the pin 259 engages the rearward end of the slot in the link 256, to move the valve member 230 in the direction of the arrow in Fig. 7, thus closing off the pipe 242 and admitting pressure fluid through the pipe 238 into the cylinder 224 to move the piston 222 rearwardly. This movement of the piston causes the lever 214 to be moved in a counterclockwise direction (Fig. 1) to lift the roll 24 and to move the link 263, connecting the lever 214 and the arm 260, forwardly. This forward movement of the link 263 swings the arm 260 about the pin 259 to move the valve member 230 to the left until the pipe 234 is closed off. However the valve element 248 does not move far enough at this time to uncover the pipe 242, so that the pressure fluid becomes trapped within the cylinder 224 behind the piston. During this movement of the arm 260 about the pin 259, the pin is held in the rearward end of the slot 258 by a spring 270 (Figs. 5 and 6) secured between the arm and the pipe 234. It will thus be seen that a follow-up mechanism is provided so that the piston 222 will move a distance corresponding to the amount of depression of the treadle 250. Accordingly, a slight movement of the valve member 230 may not be sufficient to lift the roll 24 entirely out of engagement with the shoe but will partially overcome the force which is exerted by the motor 184 to force the roll against the shoe bottom thereby reducing the pressure of the roll on the work. Upon release of the treadle 250 the arm 260 is returned to its original position by the spring 270. The valve element 248 now uncovers the pipe 242 allowing the fluid behind the piston to flow therethrough to dissipate the pressure thereon, and the roll 24 is again forced against the work under full pressure by the motor 184.

In order to move the roll upwardly at the completion of the leveling operation, mechanism operated by the jack-operating motor 46 and illustrated in Figs. 3, 4 and 5 is provided. The pin 259 connecting the link 256 and the arm 260 extends outwardly from the arm and is connected by a short link 280 to a rod 282 which is supported for sliding movement by bosses 284 carried by a bell-crank lever 286 pivoted at 288 to the machine frame. Pivoted to the upper end 10 of the bell-crank lever 286 is a pawl 290 which locks the rod 282 against rearward movement relatively to the lever when the pawl is in operative position. The position of the pawl relatively to the bell-crank lever is controlled by an 15 arm 292 movable with the pawl and held by a spring 294 against an adjustable stop screw 296 carried by a fixed bracket 298. During the leveling operation, the bell-crank lever 286 is held in a position disposed somewhat clockwise of that 20 shown in Fig. 4, in engagement with the upper end of the bracket 298, by a spring 300 connected between the bell-crank lever and a pin 302 secured to the cylinder 46. Accordingly, during 25 the leveling operation, the arm 292 in cooperation with the stop screw 296 holds the pawl 290 out of operative relationship with the rod 282 so that this rod is free to slide relatively to the bell-crank lever in response to movements imparted to the arm 260 when the heightwise position of the leveling roll 24 varies during the 30 leveling operation because of differences in height of various portions of the shoe bottom.

Carried by the forward end of the previously mentioned piston rod 42 is a bracket 304 having a rearwardly extending arm carrying a roll 306 which cooperates with a cam slot 308 formed in the lower arm of the bell-crank lever 286 to cause movement of the bell-crank lever in a counterclockwise direction (Fig. 4) upon rearward movement of the roll 306 into the position shown. This movement takes place as the jack is moved by the piston 44 and the piston rod 42 into loading position at the completion of the leveling operation. This movement of the bell-crank lever moves the upper end of the arm 292 away from the screw 296 and permits movement 35 of the arm 292 by the spring 294 relatively to the lever to move the pawl 290 into gripping relationship with the rod 282. Upon further movement of the bell-crank lever by the jack, the rod 282 is moved forwardly therewith, causing the arm 260 to turn in a clockwise direction (Figs. 3 and 5) about its connection to the link 263 to move the valve member 230 forwardly and to move the motor 220 to the fluid under pressure, thus causing the roll 24 to be elevated. Upon reverse movement of the jack to carry the shoe under the leveling roll, the roll 306 (Fig. 4) moves out of the slot 308 and the bell-crank lever 286 is moved in a clockwise direction by the 40 spring 300 to free the rod 282 from the pawl 290, whereupon the spring 210 (Figs. 3 and 6) returns the valve member 230 to the position shown in Fig. 7 and the leveling roll is forced downwardly by the motor 184 into engagement with the work.

Tipping of the leveling roll is effected by a fluid-pressure motor generally similar in construction to the jack-operating motor and including a piston 320 (Fig. 7) slidable in a vertically disposed cylinder 322. Projecting upwardly from the cylinder is a piston rod 324 connected by a link 326 (Fig. 1) to the lever 176 secured to the shaft 162 by which the leveling roll is supported. Flow of pressure fluid into 45

the cylinder 322, through pipes 328 and 330 connected respectively to the lower and upper portions of the cylinder, is controlled by a valve member 332 similar to the valve member 53 of Fig. 7. Upon upward movement of the valve member, fluid under pressure flows from the manifold 60 through pipes 192, 334, 336 and 328 into the lower end of the cylinder 322 to move the piston upwardly and tip the leveling roll in a counterclockwise direction (Fig. 1). Downward movement of the valve member 332 causes the pressure fluid to flow through a pipe 338 and the pipe 330 into the upper portion of the cylinder, causing the leveling roll to tip in the opposite direction.

The valve member 332 is operated by a hand lever 340 (Fig. 1) which is pivoted at 341 to the machine frame and is connected by a link 342 to the upper end of a bell-crank lever 344 pivoted at 346 to the frame of the machine. The lower arm of the bell-crank lever 344 is connected by a link 348 to one end of a lever 350, the opposite end of which is pivoted to the lower end of an arm 352 of the lever 176. The valve member 332 includes a valve stem 358 pivoted to an intermediate portion of the lever 350. Upon rearward movement of the operating lever 340 the lever 350 is swung in a counterclockwise direction (Fig. 1) about its connection to the arm 352 of the lever 176 to move the valve stem 358 upwardly, thus introducing fluid under pressure into the lower end of the cylinder 322. This causes upward movement of the piston 320, tipping the leveling roll in a counterclockwise direction (Fig. 1) and causing counterclockwise movement of the arm 352 of the lever 176 to swing the lever 350 about its connection to the link 348, thereby moving the valve member 332 back toward its original position. Accordingly, the degree of tipping movement of the roll will depend upon the amount of displacement of the valve member 332 which is directly proportional to the extent of movement of the operating lever 340. It will be understood that forward movement of the operating lever 340 causes movement of the valve member 332 downwardly so that the leveling roll is tipped in the opposite direction.

Provision is made for insuring that the leveling roll is in a horizontal position when the jack is in its loading position so that at the beginning of the leveling operation the leveling roll will not exert undesirable pressure along either edge of the sole at the toe portion. For this purpose the forward end of the arm 146, movable with the jack, is provided with an adjustable screw 370 engageable with an arm 372 extending rearwardly from the operating lever 340 to cause this lever to move rearwardly to the position shown in the event that the lever is in its forward position at the conclusion of the leveling operation. Should the operating lever be in a rearward position at the end of the leveling operation, the forward end of the arm 146 will engage the lever when the jack is moved to loading position, thereby by moving the operating lever forwardly into the position shown. Accordingly, irrespective of the position in which the operator leaves the lever 340 at the end of the leveling operation, it will be moved into the position shown in Fig. 1 by the jack when the jack moves into its loading position thereby to move the leveling roll into horizontal position.

In the operation of the machine, a shoe is placed on the jack 22, the parts being in the

positions shown in Fig. 1 when the machine is at rest. The operating lever 84 is then moved rearwardly, swinging the downwardly extending arm 80 to which it is connected in a direction to move the valve stem 84 forwardly and admitting pressure into the cylinder 48 rearwardly of the piston 44, which thus moves the jack rearwardly to carry the shoe under the leveling roll 24. At the beginning of this movement of the jack, the roll 306 (Fig. 4) moves out of the cam slot 308 in the lever 286 and the spring 300 moves this lever in a direction to free the rod 282 from the action of the pawl 290, whereupon the spring 270 (Fig. 5) moves the valve stem 262 rearwardly to shut off the flow of pressure fluid from the pump to the cylinder 224 (Fig. 7), and the motor 184 moves the leveling roll into engagement with the shoe bottom. At the same time the pin 110 carried by the arm 90 rides over the top of the latch 102 and the spring 106 moves the latch into position, preventing the operating lever 84 from being subsequently moved sufficiently far forwardly to carry the shoe forwardly of the leveling roll until the treadle 122 is depressed. The roll 144, carried by the arm 146 movable with the jack, moves out of the cam slot 142 of the arm 140 at the beginning of the rearward movement of the jack, thus moving the arm 140 in a clockwise direction and closing the by-pass valve 128 so that the full capacity of the pump is available for the leveling operation. The jack is now moved forwardly and rearwardly by corresponding movements of the operating lever 84 and the roll is tipped as desired by forward and rearward movements of the operating lever 340. If it is desired at any time to reduce the pressure of the leveling roll 24, the treadle 250 may be depressed to admit fluid behind the piston 222 which is moved an amount corresponding to the amount that the treadle is depressed to reduce the effectiveness of the motor 184 accordingly. If the treadle 250 is depressed sufficiently the leveling roll may be lifted out of engagement with the shoe bottom. This action may be desired if the type of shoe being leveled requires the leveling pressure to be withdrawn at certain portions of the shoe bottom.

At the completion of the leveling operation, the operating lever 84 is moved forwardly and the treadle 122 is depressed, thus releasing the latch 102 and permitting the forward movement of the lever 84 far enough to move the jack into loading position. During this movement of the jack, the roll 306 enters the cam slot in the lever 286 (Fig. 4) to move this lever in a counterclockwise direction which causes operation of the motor 220 to lift the leveling roll. At the same time the lever 340 is moved into its neutral position and the by-pass valve 128 is opened to reduce the load on the pump 62 while maintaining sufficient pressure in the system to hold the leveling roll in its elevated position in readiness for the next leveling operation.

Having thus described my invention, what I claim as new and desire to secure by Letters Patent of the United States is:

1. In a leveling machine, a shoe support, a leveling tool, means for effecting relative movement of the shoe support and the leveling tool in directions lengthwise of a shoe on the support to cause the tool to operate progressively along the shoe bottom, and fluid-pressure-operated means acting on said tool to force it against the shoe bottom.

2. In a leveling machine, a shoe support, a lev-

eling tool, means for effecting relative movement of the shoe support and the leveling tool in directions lengthwise of a shoe on the support to cause the tool to operate progressively along the shoe bottom, fluid-pressure-operated means for forcing said tool against the shoe bottom, and operator-controlled means for varying the pressure of the tool against the shoe bottom during the leveling operation.

3. In a leveling machine, a shoe support, a leveling tool, means for effecting relative movement of the shoe support and the leveling tool in directions lengthwise of a shoe on the support to cause the tool to operate progressively along the shoe bottom, fluid-pressure-operated means for forcing said tool against the shoe bottom, and other fluid-pressure-operated means under the control of the operator for varying the pressure of the tool on the shoe bottom during the leveling operation.

4. In a leveling machine, a shoe support, a leveling tool, power-operated means for effecting relative movement of the shoe support and the leveling tool in directions lengthwise of a shoe on the support to cause the tool to operate progressively along the shoe bottom, fluid-pressure-operated means acting normally to force said leveling tool downwardly into engagement with the shoe bottom, and means under the control of the operator for raising said tool against the action of said fluid-pressure-operated means.

5. In a leveling machine, a shoe support, a leveling tool, power-operated means for effecting relative movement of the shoe support and the leveling tool in directions lengthwise of a shoe on the support to cause the tool to operate progressively along the shoe bottom, fluid-pressure-operated means acting normally to force said leveling tool downwardly into engagement with the shoe bottom, means under the control of the operator for raising said tool against the action of said fluid-pressure-operated means, and operator-controlled means for varying the force with which the tool is pressed against the bottom of the shoe.

6. In a leveling machine, a shoe support, a leveling tool, power-operated means for effecting relative movement of the shoe support and the leveling tool in directions lengthwise of a shoe on the support to cause the tool to operate progressively along the shoe bottom, fluid-pressure-operated means acting on said tool to force it against the shoe bottom, and operator-controlled means acting on said tool in opposition to said fluid-pressure means effective to reduce the pressure of the tool on the shoe bottom or to move the tool out of engagement with the shoe bottom.

7. In a leveling machine, a shoe support, a leveling tool, power-operated means for effecting relative movement of the shoe support and the leveling tool in directions lengthwise of a shoe on the support to cause the tool to operate progressively along the shoe bottom, fluid-pressure-operated means acting on said tool to force it against the shoe bottom, and operator-controlled means for varying the effectiveness of said fluid-pressure-operated means during the leveling operation.

8. In a power-operated machine, a support movable to present work in position to be operated upon, a tool for thereafter operating upon the work, mechanism arranged to be operated by pressure of fluid against it for effecting such movement of said support, a pump for supplying

fluid under pressure to said mechanism, means for normally diverting a portion of the operating fluid from said mechanism thereby to reduce the pressure of the fluid supplied to said mechanism to a predetermined low value, and means for rendering said last-named means inoperative at a predetermined time in the movement of the support prior to engagement of the tool with the work.

9. In a power-operated machine, a support movable to present work in position to be operated upon, a tool for thereafter operating upon the work, mechanism arranged to be operated by pressure of fluid against it for effecting such movement of said support, a pump for supplying fluid under pressure to said mechanism, means acting normally to cause a recirculation of a portion of the operating fluid through said pump to cause the pressure of the fluid supplied to said mechanism to be reduced to a predetermined low value, and means for closing said recirculating means at a predetermined time in the relative movement of the support and tool prior to the engagement of the tool with the work.

10. In a power-operated machine, a support movable to present work in position to be operated upon, a tool for thereafter operating upon the work, mechanism arranged to be operated by pressure of fluid against it for effecting such movement of the work support, a pump for supplying fluid under pressure to said mechanism, a restricted by-pass connecting the high-pressure and low-pressure sides of said pump, a valve for controlling the flow of operating fluid through said by-pass and arranged when open to cause the pressure of the operating fluid to be reduced to a predetermined low value, means for controlling the flow of fluid from said pump to said mechanism, means operative in response to the initial operation of said mechanism by the fluid under low pressure for closing said valve to cause the pressure of the operating fluid to be increased, and a pressure-relief valve for determining the maximum pressure of the operating fluid.

11. In a power-operated machine, a support movable to present work in position to be operated upon, a tool for thereafter operating upon the work, mechanism arranged to be operated by pressure of fluid against it for effecting such movement of the work support, a pump for supplying fluid under pressure to said mechanism, a restricted by-pass connecting the high-pressure and low-pressure sides of said pump, a valve for controlling the flow of fluid through said by-pass and arranged when open to cause the pressure of the operating fluid to be reduced to a predetermined value, means for controlling the flow of fluid through said by-pass when said valve is open to regulate the minimum pressure of the operating fluid, means for controlling the flow of fluid from said pump to said mechanism, means operative in response to the initial operation of said mechanism by the fluid under low pressure for closing said valve to cause the pressure of the operating fluid to be increased, and a pressure-relief valve for determining the maximum pressure of the operating fluid.

12. In a leveling machine, a shoe support, a leveling tool, means for effecting relative movement of the shoe support and the leveling tool in directions lengthwise of a shoe on the support to cause the tool to operate progressively along the shoe bottom, means for holding said leveling tool in an elevated position at the beginning of a leveling operation, and fluid-pressure-operated

means for moving said leveling tool downwardly into engagement with the bottom of a shoe on the support in response to such relative movement of the shoe support and the leveling tool.

13. In a leveling machine, a shoe support, a leveling tool, means for moving said shoe support in directions lengthwise of a shoe thereon to cause said leveling tool to operate progressively along the shoe bottom, and fluid-pressure means for holding said leveling tool initially in a position higher than it occupies in operating upon the shoe and for moving it automatically into engagement with the toe end of the shoe bottom at a predetermined time in the movement of said shoe support prior to the operation of said tool upon the shoe.

14. In a leveling machine, a shoe support, a leveling tool, means for moving said shoe support in directions lengthwise of a shoe on the support to cause the tool to operate progressively along the shoe bottom, fluid-pressure-operated means acting on said tool to force it against the shoe bottom, and means for lifting the tool out of engagement with the shoe bottom in response to movement of the shoe support to carry the shoe out of engagement with the leveling tool.

15. In a leveling machine, a shoe support, a leveling tool, power-operated means for moving said shoe support in directions lengthwise of a shoe on the support to cause the tool to operate progressively along the shoe bottom, fluid-pressure-operated means acting on said tool to force it against the shoe bottom, means for lifting the tool out of engagement with the shoe bottom in response to movement of the shoe support to carry the shoe out of engagement with the leveling tool, and operator-controlled means for actuating said lifting means at any time during the operation of the machine.

16. In a leveling machine, a shoe support, a leveling tool, means for moving said shoe support in directions lengthwise of a shoe on the support to cause the tool to operate progressively along the shoe bottom, and fluid-pressure-operated means arranged automatically to move the leveling tool into engagement with the shoe bottom in response to rearward movement of the shoe support from an initial position to carry the toe end of the shoe into a predetermined relationship with the leveling tool.

17. In a leveling machine, a shoe support, a leveling tool, power-operating means for moving said shoe support in directions lengthwise of a shoe on the support to cause the tool to operate progressively along the shoe bottom, and fluid-pressure-operated means controlled by said power-operated means to move the leveling tool into engagement with the shoe bottom in response to rearward movement of the shoe support from an initial position to carry the toe end of the shoe into a predetermined position with relation to the leveling tool.

18. In a leveling machine, a shoe support, a leveling tool, means for moving said shoe support in directions lengthwise of a shoe on the support to cause the tool to operate progressively along the shoe bottom, fluid-pressure-operated means arranged automatically to move the leveling tool into engagement with the shoe bottom in response to rearward movement of the shoe support from an initial position to carry the toe end of the shoe into a predetermined relationship with the shoe support, and operator-controlled means for varying the force with which the tool is pressed

against the bottom of the shoe during the leveling operation.

19. In a leveling machine, a shoe support, a leveling tool, fluid-pressure-operated means for moving said shoe support in directions lengthwise of a shoe on the support to cause the tool to operate progressively along the shoe bottom, and second fluid-pressure-operated means controlled by said first-named fluid-pressure-operated means to move the leveling tool into engagement with the shoe bottom in response to rearward movement of the shoe support from an initial position to carry the toe end of the shoe into a predetermined position relatively to the leveling tool.

20. In a leveling machine, a shoe support, a leveling tool, fluid-pressure-operated means for moving said shoe support in directions lengthwise of a shoe on the support to cause the tool to operate progressively along the shoe bottom, second fluid-pressure-operated means controlled by said first-named fluid-pressure-operated means to move the leveling tool into engagement with the shoe bottom in response to rearward movement of the shoe support from a rearward position to carry the toe end of the shoe into a predetermined position relatively to the leveling tool, and operator-controlled means for varying the force with which the tool is pressed against the bottom of the shoe during the leveling operation.

21. In a leveling machine, a shoe support, a leveling tool, power-operated means for moving said shoe support in directions lengthwise of a shoe on the support to cause the tool to operate progressively along the shoe bottom, fluid-pressure-operated means acting on said tool to force it against the shoe bottom, and fluid-pressure-operated means arranged automatically to lift the tool out of engagement with the shoe bottom in response to forward movement of the shoe support to carry the toe end of the shoe into a predetermined position relatively to the leveling tool.

22. In a leveling machine, a shoe support movable to carry a shoe mounted thereon into position to be operated upon, a leveling tool for thereafter operating upon the shoe, fluid-pressure-operated mechanism for effecting such movement of the shoe support, fluid-pressure-operated mechanism for forcing the tool into engagement with the shoe bottom, and means for increasing the pressure of the operating fluid as the shoe support is thus moved.

23. In a leveling machine, a leveling tool, a shoe support movable toward said leveling tool to carry a shoe mounted thereon into position to be operated upon by said tool, said tool being movable to apply pressure to the shoe, mechanism arranged to be operated by pressure of fluid against it for effecting such movements of the shoe support and the tool, and means for increasing the pressure of the operating fluid in response to the movement of the support to carry the shoe into position to be operated upon.

24. In a leveling machine, a leveling tool, a shoe support movable toward said leveling tool to carry a shoe mounted thereon into position to be operated upon by said tool, said tool being movable to apply pressure to the shoe, mechanism arranged to be operated by pressure of fluid against it for effecting such movement of the shoe support and the tool, means for increasing the pressure of the operating fluid in response to the movement of the support to carry the shoe into position to be operated upon, and means arranged automatically to lift the tool out of engagement with the shoe in response to movement of the shoe support to carry

the toe end of the shoe into a predetermined position relatively to the leveling tool.

5 25. In a leveling machine, a leveling tool, a shoe support movable toward said leveling tool to carry a shoe mounted thereon into position to be operated upon by said tool, said tool being movable to apply pressure to the shoe, mechanism arranged to be operated by pressure of fluid against it for effecting such movements of the shoe support and the tool, means for increasing the pressure of the operating fluid in response to the movement of the support to carry the shoe into position to be operated upon, and operator-controlled means for varying the force with which the tool is pressed against the bottom of the shoe.

15 26. In a leveling machine, a shoe support movable to carry a shoe mounted thereon into position to be operated upon, a leveling tool for thereafter operating upon the shoe, mechanism arranged to be operated by pressure of fluid against it for effecting such movement of the support, a pump for supplying fluid under pressure to said mechanism, a pressure relief valve for determining the maximum pressure of the operating fluid supplied by said pump, a by-pass connecting the high-pressure and low-pressure sides of said pump and arranged when open to cause the pressure of the operating fluid to be reduced to a predetermined minimum value, means controlling the flow of pressure fluid from said pump to said mechanism, and means operated in response to the initial movement of said shoe support by said mechanism under low pressure for closing said by-pass to cause an increase in the pressure of the operating fluid available for operating said mechanism.

30 27. In a leveling machine, a shoe support movable to carry a shoe mounted thereon into position to be operated upon, a leveling tool for thereafter operating upon the shoe, mechanism arranged to be operated by pressure of fluid against it for effecting such movement of the support, a pump for supplying fluid under pressure to said mechanism, a pressure relief valve for determining the maximum pressure of the operating fluid supplied by said pump, means normally by-passing a portion of the pressure fluid from the high to the low-pressure side of said pump to cause operating fluid to be supplied to said mechanism initially at a value lower than that determined by said relief valve, and means for automatically rendering said last-named means inoperative to by-pass said fluid at a predetermined time in the movement of the shoe support to carry the shoe into position to be operated upon to cause the pressure of the operating fluid to be increased.

35 40 45 50 55 60 65 70 75 80 85 90 95 28. In a leveling machine, a shoe support movable to carry a shoe mounted thereon into position to be operated upon, a leveling tool for thereafter operating upon the shoe, mechanism arranged to be operated by pressure of fluid against it for effecting such movement of the shoe support, a pump for supplying fluid under pressure to said mechanism, a restricted by-pass connecting the high-pressure and low-pressure sides of said pump, a valve controlling the flow through said by-pass and arranged when open to cause the pressure of the operating fluid to be reduced to a predetermined value, means for controlling the flow through said by-pass when said valve is open to regulate the minimum pressure of the operating fluid, means for controlling the flow of fluid from said pump to said mechanism, means operative in response to the initial operation of said mechanism by the fluid under low pressure to

move said shoe support for closing said valve to cause the pressure of the operating fluid to be increased, and a pressure-relief valve for determining the maximum pressure of the operating fluid.

29. In a leveling machine, a shoe support, a leveling tool, power-operated means for effecting relative movement of the shoe support and the leveling tool in directions lengthwise of a shoe on the support to cause the tool to operate progressively along the shoe bottom, a motor connected to said leveling tool for forcing it into engagement with the shoe bottom, a second motor connected to said leveling tool for moving the tool out of engagement with the shoe bottom, and means for varying the relative power output of said motors to vary the pressure of the tool on the shoe bottom.

30. In a leveling machine, a shoe support, a leveling tool, power-operated means for moving said shoe support in directions lengthwise of a shoe on the support to cause the tool to operate progressively along the shoe bottom, a motor connected to said leveling tool for forcing it into engagement with the shoe bottom, a second motor connected to the leveling tool for moving it out of engagement with the shoe bottom against the action of the first-named motor, means under the control of the operator for varying the effectiveness of the second motor during the leveling operation, and means for operating the second motor at maximum capacity automatically in response to movement of the shoe support to carry the shoe out of engagement with the leveling tool.

31. In a leveling machine, a shoe support, a leveling tool, power-operated means for effecting relative movement of the shoe support and the leveling tool in directions lengthwise of a shoe on the support to cause the tool to operate progressively along the shoe bottom, a fluid-pressure-operated motor connected to said leveling tool and acting to force the tool into engagement with the shoe bottom, a second fluid-pressure-operated motor connected to the leveling tool and acting to move it away from the shoe bottom, and means for varying the relative amounts of pressure fluid admitted to said motors to vary the pressure of the tool on the shoe bottom.

32. In a leveling machine, a shoe support, a leveling tool, power-operated means for effecting relative movement of the shoe support and the leveling tool in directions lengthwise of a shoe on the support to cause the tool to operate progressively along the shoe bottom, a fluid-pressure-operated motor connected to the leveling tool and acting normally to force the tool into engagement with the shoe bottom, a second fluid-pressure-operated motor connected to the leveling tool and arranged upon the admission of pressure fluid thereto to move the tool out of engagement with the shoe bottom, and means for controlling the admission of pressure fluid to said second motor.

33. In a leveling machine, a shoe support, a leveling tool, power-operated means for moving said shoe support in directions lengthwise of a shoe on the support to cause the tool to operate progressively along the shoe bottom, a fluid-pressure-operated motor connected to said leveling tool and acting normally to force the tool into engagement with the shoe bottom, a second fluid-pressure-operated motor connected to said leveling tool and arranged, upon the admission of

pressure fluid thereto, to move the tool out of engagement with the shoe bottom, operator-controlled means for admitting selected amounts of pressure fluid to the second motor, and means for automatically admitting fluid pressure to said second motor in response to movement of the shoe support to carry the shoe out of engagement with the leveling tool.

34. In a leveling machine, a shoe support, a leveling tool, power-operated means for moving said shoe support in directions lengthwise of a shoe on the support to cause the tool to operate progressively along the shoe bottom, a first fluid-pressure-operated motor acting constantly on said tool to force it into engagement with the shoe bottom, a second fluid-pressure-operated motor connected to said tool and arranged to raise it against the action of said first fluid-pressure-operated motor in response to the admission of pressure fluid into the second motor, a valve for controlling the admission of pressure fluid to said second motor, a control lever, a link connecting said control lever and said valve for opening the valve to admit fluid pressure of varying amounts to said second motor, and means connecting the leveling tool and said link for causing closing movement of the valve as the roll is elevated so that the extent of elevation of the roll is proportional to the displacement of the control lever, the connection between the link and the valve including a lost-motion connection so that no movement is imparted to the valve in response to heightwise movement of the tool as portions of the shoe bottom at varying heights from the shoe support are traversed by the leveling tool.

35. In a leveling machine, a shoe support, a leveling tool, power-operated means for moving said shoe support in directions lengthwise of a shoe on the support to cause the tool to operate progressively along the shoe bottom, a first fluid-pressure-operated motor acting constantly on said tool to force it into engagement with the shoe bottom, a second fluid-pressure-operated motor connected to said tool and arranged to raise it against the action of said first fluid-pressure-operated motor in response to the admission of pressure fluid into the second motor, a valve for controlling the admission of pressure fluid to said second motor, a control lever, a link connecting said control lever and said valve for opening it to admit fluid pressure of varying amounts to said second motor, means connecting the leveling tool and said link for causing closing movement of the valve as the roll is elevated so that the extent of elevation of the roll is proportional to the displacement of the control lever, the connection between the link and the valve including a lost-motion connection so that no movement is imparted to the valve in response to heightwise movement of the tool as portions of the shoe bottom at varying heights from the shoe support are traversed by the leveling tool, and means enabling free motion of the second fluid-pressure-operated motor in response to such motion of the tool when the valve is in closed position.

36. In a leveling machine, a shoe support, a leveling tool, power-operated means for moving said shoe support in directions lengthwise of a shoe on the support to cause the tool to operate progressively along the shoe bottom, a first fluid-pressure-operated motor acting constantly on said tool to force it into engagement with the shoe bottom, a second fluid-pressure-operated

motor connected to said tool and arranged to raise it against the action of said first fluid-pressure-operated motor in response to the admission of pressure fluid into the second motor, a valve for controlling the admission of pressure fluid to said second motor, a control lever, a link connecting said control lever and said valve for opening it to admit fluid pressure of varying amounts to said second motor, means connecting the leveling tool and said link for causing closing movement of the valve as the roll is elevated so that the extent of elevation

of the roll is proportional to the displacement of the control lever, the connection between the link and the valve including a lost-motion connection so that no movement is imparted to the valve in response to heightwise movement of the tool as portions of the shoe bottom at varying heights from the shoe support are traversed by the leveling tool, and means automatically opening said valve in response to movement of the shoe support to carry the shoe out of engagement with the leveling tool.

ALFRED S. CLARK.
